UNITED STATES PATENT OFFICE.

MAX WENZEL, OF SPREMBERG, GERMANY.

APPARATUS FOR SUCCESSIVELY SEPARATING SINGLE THREADS FROM A WARP.

1,105,867.

Specification of Letters Patent.

Patented Aug. 4, 1914.

Application filed March 13, 1914. Serial No. 824,453.

To all whom it may concern:

Be it known that I, MAX WENZEL, a citizen of the Empire of Germany, residing at No. 18 Mühlenstrasse, Spremberg, Kingdom of Prussia, Empire of Germany, have invented certain new and useful Improvements in Apparatus for Successively Separating Single Threads from a Warp, of which the following is a specification.

10 In order to separate single threads successively from a warp, use is made either of a lease, in which the devices by means of which the separation is effected operate alternately on opposite sides of the lease, or 15 there are employed devices so constructed as to be capable of removing during each working operation only a single thread, this thread being in all cases the first of a number of threads located in the same warp plane. 20 Leases must always be employed in looms in the case of multicolored or figuring warps, but they are useless for warp separating purposes in connection with warp uniting devices in all cases in which the pattern does not permit of the formation of a 25 plain weave, as in the case of an uneven number of shafts, or in the case of pointed draft of the kind known as "broken draft", in which the sides of the point consist of an 30 uneven number of threads. Single-thread picking and dividing devices, however, in order to act effectively, require to be set in every case to correspond to the particular thickness of the warp threads. It is ob- 35 vious therefore that they are wholly unsuitable for use not only in connection with warps composed of threads of varying thickness, but also with multicolored or figuring warps. In the latter case, thread 40 picking and dividing apparatus without a lease cannot be relied upon to pick or select the threads in their proper order.

Now in accordance with this invention the individual threads are successively separated from and moved out of the plane of the warp by forming a shed in the manner usually employed in the drawing-in of the warp through the harness. In accordance with this method each thread to be separated is moved out of the plane of the warp by forming the shed in accordance with a pattern which successively selects the threads in proper sequence corresponding to the drawing-in through the harness while the 55 remaining threads, whose turn for separation has not yet come, are pushed and held

back in the direction of the plane of the warp so that when the shed is closed the separated thread is lying free for gripping by the conveying device.

The pattern mechanism employed is preferably a dobby or any other suitable shaft machine.

A constructional form of an apparatus in accordance with this invention is illustrated 65 in the accompanying drawings; in which—

Figure 1 is an end view of the entire arrangement, the front of the frame being partially removed; Figs. 2 and 3 are respectively a front view and a plan of the same; Figs. 4 and 5 illustrate constructional details respectively in elevation and plan; Fig. 6 is a diagrammatic view illustrating the operation of the apparatus; and Figs. 7 to 10 are diagrammatic views of 75 portions of the mechanism in various positions.

The invention is applicable to all cases and is quite independent of the coarseness or fineness of the threads of the warp. It is 80 however especially suitable for use in those cases in which a smooth or plain weave without double threads cannot be formed, that is to say in the case of harness with an uneven number of shafts, or with pointed 85 draft of the kind known as broken draft, the sides of which consist of an uneven number of threads or with scattered or transposed draft, in all which cases two adjacent threads are at certain places both situated 90 above or below the lease bar and consequently do not cross. In the case of an uneven number of shafts the first and last threads of successive matchings lie next to each other in this manner. In the case of 95 pointed draft of the kind referred to and in the case of scattered or transposed draft such pairs of threads are to be found on the same side of the lease-bar within the matchings.

While the threads have been spoken of as raised, it is in fact immaterial whether they are moved upward or downward out of the plane of the warp.

In Fig. 1 of the drawings there is shown 105 by way of example an arrangement of five shafts $s, s', s'', s''',$ and s'''' . To enable a single thread to be separated from the lease these shafts are connected with a dobby A, which is mounted on the upper cross-beam B 110 of a frame which consists of two sides C and C' rigidly connected together by means

of a lower cross-beam D and intermediate cross-beams E and E'. On the sides C and C' are mounted upright supports H H' which carry the upper cross-bearer B. The shafts s, s', s'', s''', s'''' are subject to the action of tensional springs J, J', J'', J''', J''''', the lower ends of which are attached to blocks K, K' on the lower cross-beam D. In the sides C and C' are provided open bearings L and L' for the pivots of the warp-beams M and M', the first of which carries the old warp and the latter the new warp to be connected with it. The old warp, together with the harness, is removed from the loom and placed in the connecting frame, in which the shafts are connected in the usual manner with the parts g on the hooks h of the dobby A. The ends of the threads of the old warp may be put into a clamp V rigidly attached to the frame, while for the ends of the threads of the new warp there may be provided in the frame another clamp W on the other side of the piecing mechanism. The ends of the warps are brought one over the other, the old warp being above and the new warp below, as shown in Fig. 1. The hooks h of the dobby A are actuated in the usual manner by means of the needles i and the cards k on the card prism l through which they are coupled in accordance with the pattern to the blade m, by means of which they are raised. The raising of the blade is effected in the well-known manner by means of the crank n on the driving shaft N which is rotatably mounted in the base of the frame, in bearings O and O' on the sides C C' and is driven by a motor. The blade and the crank are connected together by means of a connecting-rod o pivoted to the blade at p. An eccentric r on the shaft N by means of the connecting rod r' and the lever-arm r'' mounted on the prism-shaft P imparts an oscillating movement to this shaft.

The cards k of the dobby A are punched in accordance with the draft of the harness so that the raising of the threads takes place in the proper sequence. In the case of apparatus having five shafts, when the draft is straight through, the threads are raised successively in the following manner 1, 2, 3, 4, 5, 1, 2, 3, etc.

In the drawings the first shaft, for instance, forms the shed whereby all the first matching threads of the old warp are raised and consequently also that thread forming at that instant the thread subsequently to be worked of the unpiced part G^u of the old warp not yet operated on.

The part G^u of the old warp, which is not yet pieced, is now pushed and held back in the direction of the plane of the warps by means of a member, such for instance, as the vertical finger a which is movable transversely to the warp-threads of the old warp

so that by the lowering of the shaft at the closing of the shed the thread to be separated is caused to lie in front of the finger a to be carried along by it during its subsequent movement in the opposite direction, the separation of the thread being thus effected. The thread next in order is now raised, the finger a pushes and holds back the unpiced portion of the old warp, and the thread F, which is to be separated from the remainder by the lowering of its shaft is caused to lie in front of the finger a which during its conveying movement transports it to the place where it is to be used, such for instance, as the piecing mechanism G. As shown in Fig. 6 the threads G^r which have been completely joined, are held firmly in position in the well-known manner by means of a suitable retaining device b in such manner as to be incapable of interfering with the proper action of the mechanism Q.

The finger a is provided at the side remote from the threads G^u not yet joined with a hook-like projection d (Figs. 4, 6 to 10) which prevents the gripped thread from slipping.

To sum up:—The thread F which is next to be joined, is raised by the dobby A in such manner as to be brought over the path of the finger a, which, moving in the direction of the unconnected warp threads G^u, can consequently pass beneath the raised thread F in order that it may push back the threads not yet connected (Fig. 7). When now during that movement of the dobby which effects the closing of the shed the thread F is again brought into the plane of the warp (Fig. 8) it will lie in front of the finger a, that is to say, it will be separated from the remainder of the threads. The finger a now executes its movement toward the delivering or operating point Q and carries along the thread F lying in front of it, until this thread is gripped in the well-known manner, for instance, by the catch R of the mechanism Q (Fig. 9). The finger a will now repeat its movement to push back the warp-threads which are not yet ready for it, while the dobby again forms the shed, this time with the shaft next in sequence. By this means the next thread F' (Fig. 10) is raised out of the plane of the warp and above the path of the finger a, which now again pushes back the threads G^u not yet ready. When the shed is closed the thread F' is again brought into the plane of the warp so as to lie in front of the finger, which, during its conveying or delivering movement will carry it along and transfer it to the catch of the operating mechanism. The process just described is repeated in the case of each successive thread.

The operating mechanism such for instance as the piecing mechanism Q is likewise actuated from the shaft N by a number

of pairs of bevel wheels 2 and 3, 4 and 5 and 6 and 7, and by the shaft 8 and 9, the latter of which actuates the transverse main shaft 10 of the piecing mechanism Q. The 5 ratio of transmission from N to 10 is 1:1, so that the dobby and the piecing apparatus work synchronously. The movement of the finger α is derived from the main shaft 10 of the mechanism Q, which by means of pairs 10 of bevel wheels 11 and 12, 13 and 14 and of an intermediate shaft 15 (Figs. 4, 5) actuates a cam-shaft 16, the cam 17 of which acts on a two-armed oscillating lever 20 pivoted on a fixed stud 19 in opposition to the action 15 of a spring 18. The lever 20 actuates a connecting rod 21 that slides on guides 22, 23, and to which a rectilinear movement is imparted by the cam 17 in coöperation with the spring 18. The piecing mechanism Q 20 can be disposed in the well-known manner on guide-rods T, T' attached to the sides C, C' of the frame and its step-by-step displacement is effected by means of a screw-spindle U rotatable but not axially movable 25 in the frame and passing through a nut U' on the piecing mechanism. The step-by-step rotation of the screw-spindle is effected from the shaft N by means of an eccentric 24, the rod 25 of which engages with a slot 30 in the arm 26 of a lever 27 which is pivoted on the smooth end of the screw-spindle U and the pawl 28 of which engages with the ratchet wheel 29 mounted on the end of this 35 screw-spindle. The catch R of the piecing mechanism consists of a hook, which is rotatable in a vertical plane and is actuated by means of a cam-disk on the shaft 15 (Figs. 4 and 5).

What I claim is:

40 1. In an apparatus for separating single threads successively from a warp drawn in the harness, a warp beam (M) for carrying the old warp, harness (as S, S', S'', S''', S''') into which the old warp is drawn, means (A) for operating the harness, means for gripping the thread ends of the old warp and for holding the old warp in a horizontal plane; a frame for receiving the warp beam, the harness-operating means and the means 45 for holding the warp, means for operating the harness-operating means to form a shed, means for pressing back non-pieced warp threads when the shed is open and for moving away the thread separated by the formation of the shed from the other threads after the shed is closed, substantially as described and shown.

2. In an apparatus for separating single threads successively from a warp drawn in the harness, a warp beam (M) for carrying the old warp, harness into which the old warp is drawn, a shaft arrangement (A) for operating the harness, means for gripping

the thread ends of the old warp and for holding the old warp in a horizontal plane; 65 a frame for receiving the warp beam, the shaft arrangement and harness and the means for holding the warp, means for operating the shaft arrangement to form a shed, means for pressing back non-pieced 70 warp threads when the shed is open and for moving away the thread separated by the formation of the shed from the other threads after the shed is closed, substantially as described and shown. 75

3. In an apparatus for separating single threads successively from a warp drawn in the harness, a warp beam (M) carrying the old warp, harness into which the old warp is drawn, means for operating the harness, 80 means for gripping the thread ends of the old warp and for holding the old warp in a horizontal plane; a frame for receiving the warp beam, the harness-operating means, the harness and the means for holding the 85 warp, means for operating the harness-operating means to form a shed, a finger for pressing back the non-pieced warp threads when the shed is open, means for reciprocating that finger crosswise relatively to the 90 warp threads alternately against the non-pieced warp threads and away from them, the first motion taking place after the opening of the shed and the second after the closing thereof, substantially as described and 95 shown.

4. In an apparatus for separating single threads successively from a warp drawn in the harness, a warp beam (M) for carrying the old warp, a harness into which the old warp is drawn, a dobby (A) for operating the harness, means for gripping the thread ends of the old warp and for holding the old warp in a horizontal plane; a frame for receiving the warp beam, the dobby with 100 the harness and the means for holding the warp, means for operating the dobby to form a shed, a finger for pressing back the non-pieced warp threads when the shed is open, means for reciprocating the said finger 105 crosswise relatively to the warp threads, alternatingly against the non-pieced warp threads and away from them, the first motion taking place after the opening of the shed and the second after the closing thereof, and a hook at the top part of said finger 110 for preventing the thread gripped by the finger from slipping off therefrom, substantially as described and shown.

In testimony whereof I affix my signature 120 in presence of two witnesses.

MAX WENZEL.
